UNITED STATES PATENT OFFICE.

WILLIAM E. DIPPERT, OF DES MOINES, IOWA.

DESIGN FOR A TRACE-CARRIER.

SPECIFICATION forming part of Design No. 29,515, dated October 18, 1898.

Application filed September 12, 1898. Serial No. 690,806. Term of patent 14 years.

To all whom it may concern:

Be it known that I, WILLIAM E. DIPPERT, a citizen of the United States of America, and a resident of Des Moines, Polk county, Iowa, 5 have invented and produced a new and original Design for Trace-Carriers, of which the following is a specification.

The object of this invention is to provide a new and original design for a useful article 10 of manufacture—a trace-carrier.

My invention consists of the design for a trace-carrier in which the medially-located longitudinally-arched guard is a novel and essential factor.

15 In the drawings, Figure 1 is a plan illustrating my complete design. Fig. 2 is a vertical longitudinal section on the indicated line 2 2 of Fig. 1. Fig. 3 is a cross-section on the indicated line 3 3 of Fig. 1. Fig. 4 is a cross-section on the indicated line 4 4 of Fig. 1.

20 My design for trace-carriers embodies a base-plate 10 of skeleton character and generally rectangular form. The major portion of the base-plate is rounded at the corners to give an irregularly circular effect, and the 25 minor portion 11 of the base-plate projects from the major portion thereof, is restricted as to width, and provided with corners approximately square. A rectangular opening 30 12 is formed in the minor portion 11 of the base-plate, and one margin of said opening is provided by a rectangularly arched or forked standard 13, projecting materially above the horizontal plane of the base-plate. 35 A triangularly-arched standard 14 rises from

the end portion of the major portion of the base-plate opposite to the standard 13, and the apex of the standard 14 is connected to the center of the top of the standard 13 by a guard 15. The guard 15 is located medially 40 of and above the base-plate and extends longitudinally thereof. The guard 15 is also arched upwardly between its ends. Standards 16 17 extend upwardly and inwardly from the central portions of the sides of the 45 base-plate approximately one-half the distance from the base-plate to the apex of the guard, and cross heads 18 19 are formed on and approximately at right angles to the upper ends of the said standards below and on 50 either side of the guard. The cross-heads 18 19 are provided with longitudinally-arranged downwardly-extending lips 20 21 near their rear ends, forming concavities in the lower faces of said cross-heads, and the forward 55 ends of the cross-heads are bossed or enlarged in cross-section. The base-plate 10 is also provided with longitudinal slots 22 23 in its opposite sides, which slots cross the planes of projection of the standards 16 17. 60

I claim as my invention—

The design for a trace-carrier substantially as herein shown and described.

Signed by me, at Des Moines, Iowa, this 30th day of August, 1898.

WILLIAM E. DIPPERT.
